UNITED STATES PATENT OFFICE

2,646,253

DIRECTIONAL DRILLING

Daniel S. Johnston, Rolling Hills, Calif., assignor
to Signal Oil and Gas Company, Los Angeles,
Calif., a corporation of Delaware

Application January 3, 1950, Serial No. 136,533

4 Claims. (Cl. 255—1.6)

1

This application is a continuation-in-part of Serial No. 642,080, filed January 18, 1946, now abandoned.

This invention relates to a method of drilling directional deviated bore holes in the earth, particularly deviated bore holes drilled in the earth for production of petroleum. These bore holes are characterized by the fact that their course in the earth is in a direction other than vertical, and thus their axes are directed in such manner that they make an angle with the vertical called "vertical deviation" and are directed in the azimuthal plane. This direction, referred to as north or 0° azimuth, in the azimuthal plane is called "azimuthal deviation." In drilling parlance the vertical deviation is also called "drift" and the azimuthal deviation is also called "the direction or deviation of the bore hole."

In drilling a deviated bore hole, it is the present practice to direct the bore hole to pass in a large arcuate path to a desired point in a target formation. Thus, the course of the well results in the axis having an increasing vertical deviation or drift as the bore is advanced. This procedure is termed "building" or "increasing drift angle." The rate of increase of drift and the maximum desirable angle of drift is determined by a number of considerations. Among the most important and controlling is the slenderness ratio of the mechanical system of casing, drill pipe, and also the phenomenon of key seating.

As a practical matter, the maximum rate of increase of drift usually employed in commercial practice is about 3-4° per hundred feet of bore hole and the usual maximum deviation found desirable is about 60-70°. These limits are dependent upon and are determined by the physical characteristics of the bore hole and the size and character of casing and drill tubing employed in drilling wells. Ordinarily, for conventional tubing and casing the practical limit is as indicated. The frictional resistance to the introduction of casing in holes of much greater degree of curvature, or greater total deviation, is excessively large and largely impractical.

It is frequently conventional practice to start a deviated hole as a vertical bore through the unconsolidated formations lying at the surface. Depending on the location and the course desired for the bore, such vertical bores may be up to 1600' or more. After the desired vertical depth is attained, drift angle is built up. Thus, depending upon the depth of the vertical bore and the rate of building of drift angle, the bottom of the hole when the maximum drift angle is

2

built may be at some distance from the target. It is then conventional to continue the bore in a straight course at a constant drift angle.

It is frequently desirable to end the bore hole as a vertical bore. This is desirable in order to space the bore holes for efficient drainage of the formations. When penetrating a formation at an angle to the vertical, the bore hole intervals at the top of the formation will, in practically all cases, be different from the bottom of the formation. If they are spaced for efficient drainage at the top or bottom, the spacing at the other end of the formation will be inefficient since the bore holes in going through the formation will in practically all such cases make an angle with each other.

Where there is a plurality of oil horizons separated by non-productive zones, it is usually desirable to penetrate the zones at a predetermined position of the structure for maximum efficiency of production. Since in the usual case the various oil producing horizons have similar dips and strikes, it may be that if the course of the bore is inclined to the vertical, the bore hole will penetrate at different positions of the structure. Since, as is frequently necessary, it may be desirable to finish the hole to produce from selected formations, the position of the bore hole may be unfavorable at the selected zone. A vertical bore obviates these difficulties.

30 The reverse bend created by the decreasing of drift angle in any of the above cases increases the hazard or key seating, since the conditions for key seating are aggravated in such circumstances.

35 It is thus necessary in drilling a deviated bore hole to build and decrease angles during the course of the bore hole.

As a practical matter, it is desirable ideally to drill the bore hole so that its bent or curved axis traverses as nearly as possible a plane, hereafter called the "target plane," which intersects the well location and the point where it is desired to reach in the formation in which the bore hole is to be bottomed, i. e., the target point in the target sand. This makes not only for minimum length of hole, but also reduces difficulties in drilling.

It is, however, as a practical matter, impossible to maintain the azimuthal direction of the bore hole in the desired plane. The bore hole wanders to the left of the desired plane (i. e. develops left deviation) or to the right of the desired plane (develops right deviation) in an unpredictable manner; left and right being here and elsewhere

defined in relation to a fictitious observer at the bottom of the bore looking in the direction which the axis of the bore is to progress. The direction and degree of deviation depends upon a very large number of factors and the effect of such factors is unpredictable. Whether the hole will deviate to the right or left will depend upon one or all or a combination of the following factors: The type of drilling bit, that is, its design, whether it is a roller bit or a drag bit; if a roller bit, on the number of rollers and their sharpness; whether or not a reamer is used, and if a reamer is used, on the number of reamers and sharpness thereof, and on its design; on the length, size, and stiffness of the drill bit and drill collar placed between the reamer and bit, and above the reamer; the size and type of drill pipe string, the size of the bore hole, the relative amount of cased and uncased hole, inclination and degree of curvature of the bore; type and condition and circulation rate of the mud, the weight placed on the drilling bit, the R. P. M. of the drill bit, the lithology, bedding, dip, and strike of the formation.

Variations in any one or in combination of these factors will change the direction of the bore hole in an unpredictable manner. The prior art has thus, in order to control and predict the direction of a bore hole, relied on the setting of directionally oriented whipstock. A directional whipstock is a wedge which has the diameter of the bore hole and weighs from 1 to 2 tons. It is set in the bore hole by means of pipe and turned in the direction so that the face of the whipstock is in the desired direction. Special drills, such as knuckle jointed drills, may be employed. When the hole has been deviated, the whipstock is removed and reintroduced when the direction must again be corrected. The difficulty of setting and running whipstock, particularly in deep holes, creates a serious hazard in oil wells. The danger is great that the whipstock will wedge in the key seats or other portions of the bore holes. If this should occur, there is no way to dislodge and recover the whipstock, and the hole must be abandoned or the whipstock side-tracked. The cost of running a whipstock, even when the operation proceeds without difficulty, is great and if the whipstocks must be run with any degree of frequency, the costs may be prohibitively large.

As a result of experience in the drilling of a large number of directionally deviated wells, I have devised a drilling method whereby I may control the direction and degree of deviation of a bore hole drilled at an angle to the vertical, i. e., a directionally deviated well, in a predictable manner without the use of whipstocks.

As is well known, all bore holes for production of petroleum are drilled by clockwise rotation of a drill string. This results from the fact that all tool joints and coupling used in the making up of a drill string have right-hand threads and the direction of rotation is clockwise since a counter-clockwise rotation of the drill string may unscrew the couplings and result in parting of the drill string.

My invention may be summarized as follows: In drilling non-vertical wells, the control of the building or dropping of drift angle is obtained by mounting a guide above the drill and using drill collars of desired weight between the guide and the drill and by adjusting the compression or tension in the drill pipe above the guide, so that on rotation in one direction, either clockwise or counter-clockwise, the deviation is in one direction (left or right deviation) and this direction

of deviation may be reversed or the degree of deviation in one direction diminished by the simple expedient of reversing the direction of rotation of the drill while maintaining the above controls. The ability to drill counter-clockwise as well as clockwise arises from the use of tool joints which will not separate on rotation in either direction.

This invention will be further described in connection with the drawings, in which

Fig. 1 illustrates somewhat schematically a directionally drilled well according to my invention;

The drilling equipment employed at the well head is conventional with the exception of the mechanism of reversal of rotation of the rotary table and the use of tool joints which will not unscrew on rotation in either direction. I employ such tool joints wherever a joint is necessary in the drill string. I also provide, above the drill, a guide which is of the gage of the hole to act as a fulcrum point, and I mount drill collars between said guide and said drill.

In Fig. 1 the conventional derrick 1 is mounted on the well site floor 2 over a cellar 3 in which is set surface casing with the usual well head equipment such as mud discharge pipe 4 discharging into mud collecting trough 5. The drill pipe is rotated via the conventional kelly 6, rotated by the rotary. Usually the rotary is rotated clockwise by means of some source of motive power. I, however, introduce between the driving engine 9 and the rotary table a reversing mechanism such as a reversing gear box. Such reversing gear boxes, while not employed with drilling engines, are conventional pieces of equipment and any one of the commercially available units capable of transmitting the horsepower necessary for the drilling operation may be employed. The kelly is connected to the drill pipe 12 and the swivel 10 by tool joints 11 to be more fully described below. The drill pipe 12 is made up of sections 13, as is conventional, but I also employ tool joints 11 to be described below.

The drill pipe carries near its lower end a collar 14 of desired length and stiffness as described below and a guide 15 carrying rollers 16 of gage equal to the gage of the bore hole. The guide may be of many forms. Such guides have been used in drilling for centering purposes and other purposes heretofore. A suitable guide may be a conventional reamer such as is used in drilling of oil wells. The reamer cutters may be employed as the roller 16 or the reamer cutters may be replaced by smooth rollers of the contour of the cutters. Below the guide 15, I may position another drill collar between the guide

and the drill 18. All connections between the drill pipe sections 13, collars 14, and guide 15 and drill collars 17 and between drill collars 17 and bit 18 may be of the form of the tool joints 11 which will not separate irrespective of the direction of rotation of the drill string.

The drill string is supported as conventional on hook 19 which engages the eye of the swivel 10 and is supported on the block 20 and on drilling lines 21 which pass over the crown block 22 and is wound on a drum as is conventional. Conventional power and other equipment for operation of the line are used, as will be understood by those skilled in the art.

Drilling mud is circulated from mud storage pit 23 through line 24, pump 25, hose 26 to the swivel whereby it is circulated down the drill pipe and through the tool joints in the drill bit up the annulus between the drill pipe 12 and bore hole 27 and out the pipe 4 to the pit 23 or to any other disposal or treating plant in the manner now conventional in drilling operations.

In drilling directional holes employing my invention, I employ such a drill string and rotary system whereby I may rotate the drill in either a clockwise or a counter-clockwise direction. This, as stated, requires a tool joint which will not separate irrespective of the direction of rotation. I may employ any type of such joint, for example, the tool joint disclosed in application Serial No. 642,079 filed January 18, 1946, and in U. S. Patent No. 2,485,763. One suitable form is illustrated herein in Figs. 2 and 3.

The box 27 and pin 28 of the tool joints 11 are connected by a screw thread 29. The box and pin are either screw threaded, welded to or formed integrally with the drill pipe section 12. The external sleeve 30 is slidably fitted over the outside wall of the box and the pin and carries an internal shoulder 31 which is seated on the end 32 of the pin 28. A gasket 33 may be provided between shoulder 31 and the end 32. The sleeve 30 is screwed to the exterior wall of the box by means of screw threads 34 which are of an opposite hand to the screws connecting the box and pins to each other and to the pipe sections 13. Thus, if these are right-handed threads the threads 34 are left-handed. This construction, and others may also be employed, will result in a tool joint which will not unscrew irrespective of the direction of rotation of the drill string.

In my drilling method, employing the above or similar equipment, I am able to direct the course of the bore hole to establish the course of the bore hole in both the vertical plane and in its azimuthal plane and therefore I establish the course of the bore hole from the surface to the target formation.

I accomplish this result by controlling the drift; that is, by proper drilling techniques, I can build or decrease or maintain drift angle. Thus, the course of the bore hole in the vertical plane is established. I also am able to direct the deviation and degree of deviation right and left of the vertical plane and thus can direct the course of the bore hole in its azimuthal plane.

The building of drift angle is illustrated in Fig. 4. After the hole has been drilled vertically through the unconsolidated formation an oriented whipstock is set to establish the original direction of the bore hole at an angle and direction required to reach the ultimate target. This is conventional procedure and well understood in this art.

From this point on, I may continue the drill-

ing of the bore hole to the target sand without recourse to whipstocks. The real purpose of setting a whipstock in my method is to develop a non-vertical bore, and any other method other than the setting of a whipstock for this purpose will also be suitable for the purposes of my method.

Fig. 4 illustrates such a non-vertical bore. I use the drill string described above. The roller drill bit 18 is separated from the guide 14 by means of a relatively short collar. The length of the collar depends upon the rate of build-up of drift angle desired, the length and size of drill pipe and the degree of compressive force exerted, as described above, and also on other factors. Experience has shown that for rates of drift angle build-up of up to 3-4° per 100' and for A. P. I. drill tubing of 4½" O. D. the drill collars may be from 2 to 15', the choice being directed in the manner described below.

The drill pipe is loaded so as to place the drill pipe in compression. This, as will be understood by those skilled in the art, consists of placing the drill lines in such degree of tension that a portion or all of the weight of the drill pipe 10 rests on the drill 18. Due to the inclination of the hole and the fact that the drill pipe is in compression, the drill pipe will be bowed and rest on the bottom of the hole, as illustrated in Fig. 4.

The guide fulcruming at 16 will tend to lift the drill so as to be directed in an upward direction illustrated by the line A. The magnitude of the upward force depends upon the inclination of the hole, the compression of the drill pipe, and the length of the drill collar, and other factors described above.

Figs. 10-13 illustrate the effect of placing the drill pipe in tension. By employing long drill collars 17 and placing the drilling lines in tension to equal the weight of the drill tube down to the fulcrum point, the drill pipe may be placed in tension while the drill collar 17 is placed in compression. This procedure is identical to that employed in drilling vertical wells for controlling the weight on the drill and will be well understood by those skilled in this art.

As will be seen from Fig. 10, the net result of the tension in the drill pipe and the weight of the drill pipe and the slant of the bore hole results in a net component which bows the pipe against the upper side of the bore hole. Because of the fulcrum point 15, the drill is directed downward, as is shown by line B. The magnitude of this force depend upon factors similar to that described for force A.

When I employ the above expedients for building, maintaining, or reducing drift angle, employing conventional drill strings and rotary equipment universally now employed and which may be used only with clockwise, i. e., right-hand rotation of the drill string, I introduce, dependent upon whether the drill string is in compression or tension, in the former a right-handed deviation tendency and in the latter a left-handed deviation tendency.

This will be understood by reference to the drawings. With the drill pipe in compression, the right-hand rotation of the drill pipe will cause the pipe to ride up the right-hand side of the bore hole, where it will take a position dependent upon the compressive force and speed of rotation. The effect of this is a force G, indicated by the arrow on Fig. 6, to cause the bit to fulcrum to the left, as indicated by C on Fig. 5. The net result of this fulcruming and the upward force

illustrated in Fig. 4 is a force component D illustrated in Fig. 7. It will be seen that the right-hand rotation reduces the rate of drift build-up and causes a left-hand deviating tendency to be introduced. It will also be noted that the resultant D, that is, the resultant angular deviation, is less than that which would have been obtained if no deviating force was introduced; that is, the deviating force tends to decrease building a drift angle.

It will also be noted that since the resultant force of A and the force C depend on the magnitude of the compression for any given set of drilling conditions, an effort to increase the drift angle by loading the pipe will increase the magnitude of the drift variation.

I do not wish to be understood to say that the right-hand rotation of a pipe with the pipe in compression will necessarily cause a left-hand deviation of the drill, since many of the factors listed above may overcome this left-hand deviation factor and actually deviate the drill to the right. However, I have found that, admitting that these other factors may in such cases have a right-hand deviating effect, the right-hand rotation superimposes on these factors a left-hand deviating tendency which may reduce, cancel out, or overcome these factors, depending upon the situation. There is no way of predicting what the outcome will be. The effect of any set of conditions and the rotation of the drill pipe is unpredictable.

A similar situation exists when the drill pipe is in tension. The right-hand rotation of the pipe causes it to ride down the left-hand wall of the bore (as indicated by the arrow H, see Fig. 12) to take a position determined by the tension, weight, rigidity, and speed of rotation. The fulcruming action at 15 causes a force to be exerted to the right, as illustrated at E (see Fig. 11). The resultant of this force E and the fulcruming force B is a force F which introduces a right-hand deviation tendency and reduces the rate of drift angle decrease tendency, resulting from force B alone.

The effect of these forces is also unpredictable as is the case with the drill pipe in compression. It may be said, as a general rule, that the magnitude of drift variation and the magnitude and direction of deviation are unpredictable in any given case.

Experience with this method of drilling employing right-hand or clockwise rotation has taught that the only possible course of procedure is one of trial and error. Thus if I wish to drill so as to increase drift angle, I employ the drill pipe in compression with a relatively short drill collar, as described above and drill ahead. After drilling a short distance, for example, 30 feet, I survey the bore hole by any of the standard surveying techniques to determine the vertical deviation and the azimuthal direction of the drilled section.

If the result of the survey indicates that the rate of build-up of drift angle is insufficiently great, then additional weight may be placed on the bit by reducing the tension in the drilling lines. This increases the compressive force on the drill pipe. The drill pipe may be removed from the hole and a shorter drill collar 17 may be introduced to increase the leverage ratio. If the rate of build-up of drift angle is too great then the weight of the drill pipe on the drill is reduced to reduce the degree of compression.

In cases where the build-up of angle is largely influenced by lithological considerations, the drill

pipe may be placed in tension to introduce, as will be described below, mechanical downward components to overcome the tendency of the drill to travel up the structure.

After drilling a short distance I again survey the bore hole and if the drift angle is not correct, I may employ the expedients described above to establish the correct drift angle. But the effect of these factors on the direction of deviation is unpredictable.

Thus, if I rotate in one direction, I may build, maintain or reduce drift angle but the direction of the bore hole is unpredictable. Generally it may be said that with clockwise rotation the tendency of the bore hole when increasing drift angle or maintaining drift angle is to the left, and while decreasing drift angle to the right, as explained above, but whether it will go to the right or left or the rate of such drift depend on multitudinous factors and is unpredictable.

One is thus forced to the expedient of setting whipstocks or by the laborious procedure of trial and error varying the factors, of which, as stated above, there are some twenty or more, to find the conditions whereby the bore may be drilled at the desired drift and direction. This means is so uncertain that whipstocks are reset where direction control or variation is required. The setting of whipstocks is costly even at shallow depth. For depths in excess of about 6000', the setting of whipstocks is not only time-consuming, but highly hazardous. The danger of sticking of whipstocks which are of full hole gage is very great and if once stuck, the bore may have to be abandoned.

My drilling method employs a simple expedient for solving this dilemma. Whenever, either during drift increase, drift maintenance, or drift decrease, a survey of the bore hole shows that the bore hole is drifting in an undesired direction or at an undesired rate in the desired direction, I reverse the direction of rotation of the drill string. By so doing I counter the tendency of the drill to move in the direction in which it is going by imposing a force which tends to direct it in an opposite direction. The reversal of rotation imposes a deviation in a direction opposed to the original deviation, which may be equal to or lesser or greater than the original rate of deviation. In each case the actual deviation is a lesser or diminished deviation, and this term lesser, i. e., diminished, is used in an algebraic sense as including an equal, lesser, or opposite direction of deviation, whereby the deviation is reduced to zero, reduced in amount, but not in direction, or an opposite deviation is induced, i. e., a left deviation, if the deviation was originally right, is thus obtained.

To control the angle, i. e., deviation and direction, I place the pipe in axial stress, either compression or tension, and rotate the pipe either counter-clockwise or clockwise, depending on the direction of the stress, i. e., whether it is in tension or compression. Whenever it is desired to increase the tendency of the drill to deviate to the left or oppose the tendency to move to the right, I place the drill pipe in compression and rotate the drill pipe to the right-hand or place the pipe in tension and rotate to the left, i. e., counterclockwise. Whenever it is desired to increase the tendency of the drill to deviate to the right or oppose its tendency to move to the left, I place the drill pipe in compression and rotate the drill pipe to the left or counter-clockwise or

place the drill pipe in tension and rotate to the right.

The effect of reversal of rotation in the direction of drift is illustrated in Figs. 8 and 9 compared with Figs. 6 and 7, Figs. 14 and 15 when compared with Figs. 12 and 13.

In a set of circumstances which, on the right-hand rotation of the drill pipe, positions the pipe as in Fig. 6 with a fulcruming force G and directs the drill in the direction D as in Fig. 7, the reversal of rotation will position the pipe on the opposite side of the bore hole with a fulcruming force G' , as shown in Figs. 8, 9, and the direction of the force D' will be at 90° to the force D and its tendency will be a right tendency rather than a left tendency.

In like manner, the reversal of rotation in the case illustrated in Fig. 12, with the drill pipe in tension on the left, with a fulcruming force in the direction of the arrow H , will move the drill pipe to the opposite side of the bore hole, as shown in Fig. 14, with a fulcruming force in the direction of the arrow H' , resulting in a net compression F' which is at 90° to the component F and resulting in a left deviating tendency rather than in a right deviating tendency.

From the above considerations and explanations of the underlying principles of my new drilling technique, those skilled in the art will know how to apply my new drilling technique.

Generally stated, my invention includes a rotary drilling technique whereby a bore hole is advanced in a direction and at a desired angle to the vertical and a string of drill pipe is rotated in a bore hole having an angle inclined to the vertical in which the drill pipe is under an axial force, which may be either a compressive or a tensile force, and the lower end of the drill pipe is fulcrumed against the wall of the bore hole at a point adjacent the drill, rotating the drill in one direction while circulating mud through the drill pipe and bore hole, advancing the bore hole by advancing the drill into the earth for a material distance, surveying the bore hole, and if the direction of deviation is in an undesired direction, reversing the direction of rotation, and, if desired, also changing the magnitude and direction of the axial force, and drilling ahead, surveying the bore hole in order to determine the direction of the bore hole and by control of the direction and degree of the axial force and the direction of rotation when added to the conventional technique of rotary drilling, I may obtain and control the course of the bore hole.

I claim:

1. A method of drilling deviated bore holes which comprises advancing a drill string, which includes a drill pipe and a drill, in an inclined bore hole, fulcruming said drill string in said bore hole at a zone in said drill string above said drill, placing an axial stress in said drill string adjacent to and above said fulcrum zone, and placing said drill string below said zone and adjacent said drill in compression, rotating said drill string and advancing said drill in one azimuthal direc-

tion and reversing the direction of said rotation and thereby altering the azimuthal direction of said drill.

5 2. A method of drilling deviated bore holes which comprises advancing a drill string which includes a drill pipe and a drill, in an inclined bore hole, fulcruming said drill string in a said bore hole at a zone in said drill string above said drill, placing said drill string above and below said fulcrum zone in compression, rotating said drill string in one direction and advancing said drill in one azimuthal direction and reversing the direction of rotation of said drill string and advancing said drill in an altered azimuthal direction.

10 3. A method of drilling deviated bore holes which comprises advancing a drill string which includes a drill pipe and a drill, in an inclined bore hole, fulcruming said drill string in said bore hole at a zone in said drill string above said drill, placing said drill string above and below said fulcrum zone in compression rotating said drill string in one direction and advancing said drill in one azimuthal direction, thereafter placing the drill string adjacent to the above said zone in tension, and reversing the direction of rotation of said drill string and advancing said drill in an altered azimuthal direction.

15 4. A method of drilling deviated bore holes which comprises advancing a drill string which includes a drill pipe and a drill in an inclined bore hole at a zone in said drill string above said drill, placing the drill string adjacent to and above the said zone in axial tension and the drill string below said zone and adjacent said drill in axial compression, rotating said drill string in one direction and advancing said drill in an azimuthal direction, thereafter placing the drill string adjacent to and above said zone in axial compression and reversing the direction of rotation of said drill string and advancing said drill in an altered azimuthal direction.
